UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

APPARATUS FOR TREATING SHOE MATERIALS.

Application filed November 3, 1924. Serial No. 747,523.

This invention relates to apparatus for treating shoe materials and more particularly to apparatus by which hot moist vapor is supplied as a treating medium. The illustrated apparatus is of the type comprising a steam-chest to furnish radiant heat and to convert water into hot moist vapor at one or more treating stations.

In the manufacture of boots and shoes it is now customary to administer softening treatment to the vamp and the toe stiffener immediately prior to the pulling-over operation to condition the materials so that they may be more readily conformed to the last incidentally to said operation, and again immediately prior to the lasting operation for similar reasons. While these two treating operations are similar in purpose, they are usually practised by the use of different styles of apparatus. The reasons why one style of apparatus is used preparatory to the pulling-over operation, while another style is used preparatory to the lasting operation, are now so well known that it is not necessary at this time to discuss them and it will be sufficient to state here that the style of apparatus shown by the accompanying drawings is designed to condition the materials for the lasting operation. It is to be understood, however, that certain features of the present invention are not to be limited to use in conditioning shoe materials for lasting.

One object of the invention is to provide a steam-heated treating apparatus so organized as to insure, even when it is operating at the highest possible temperature as well as at lower temperatures, sufficient condensation of steam to maintain a supply of water of condensation to be converted into hot moist vapor to treat the work.

Another object is to organize the apparatus so that no steam can escape with the water of condensation that is discharged to be converted into vapor to treat the work.

The first of the above-mentioned objects is attained by providing a condenser thermally insulated from the steam-chest but in communication therewith to receive steam. By virtue of organizing a steam-chest and a condenser in this relation an adequate condensing effect is assured under all condi-

tions irrespective of the temperature of the steam-chest, and even if the steam-chest be maintained at a temperature considerably above the boiling temperature so that no steam would be condensed in it, the thermally insulated condenser alone will maintain a constant supply of water of condensation for the purpose stated.

The second of the aforesaid objects is attained by a novel arrangement of the piping through which the water of condensation is discharged. This piping is arranged to form a water-seal remote from thermal influence of the steam-chest, and therefore outside the latter, so that it will not be dissipated by high temperature of the steam-chest.

To obtain the desired results in the fullest degree the condenser is preferably interposed between the steam-chest and that portion of the water-pipe that forms the water-seal, to insure a sufficient quantity of sealing water under all conditions of use. Furthermore, the condenser is preferably arranged to drain all water of condensation downwardly from the bottom of the steam-chest, and the seal-forming portion of the water-pipe is preferably arranged to drain water downwardly from the condenser. In consequence of organizing the elements in the relation just specified, water of condensation will flow by gravity from the bottom of the steam-chest to the condenser at a lower level and thence to the seal-forming portion of the water-pipe at a still lower level, before going to the upper level where it is discharged.

Another object of the invention is to provide for rapid distribution of water from one area to other areas of the heated surface by which the water is to be converted into vapor. A feature relating to this aspect of the invention consists in providing said heated surface with areas sloping downwardly in opposite directions from the point at which the water is received, to divide the water into separate streams so that said streams will flow toward separate vaporizing localities. The illustrated construction is designed to provide a series of four separate treating stations, and the conduit for supplying the water is arranged to deliver

the water at a point midway between the ends of the series, that is, between the second and third stations. The sloping areas of the surface under consideration divide 5 the water into two streams one of which flows toward one end of the series while the other flows toward the opposite end, the water being thus divided so that one of said streams will serve the first and 10 second treating stations while the other serves the third and fourth stations. This feature ensures substantially uniform quantities of vapor for each of the stations under control and regulation by a single wa- 15 ter valve, and counteracts a harmful practice that prevails with apparatus in which the vapor is supplied unequally to several treating stations. The said practice consists in regulating the supply of vapor to pro- 20 duce a visible excess at those stations that receive the smallest quantities, and the result is that the larger quantities supplied to the other stations stain and sometimes burn the shoes undergoing treatment.

25 Other features of the invention are shown by the drawings and are hereinafter described and claimed.

Referring to the drawings,

Fig. 1 is a front elevation, partly broken 30 away to show internal construction, of an apparatus embodying the several features of this invention;

Fig. 2 is an end elevation of said apparatus; and

35 Fig. 3 is a perspective view showing the preferred type of work support adjusted to support a shoe for treatment in an inverted position.

A cast iron unit 10, including an elongated, horizontal steam-chest, is formed with bosses 12 one at each end to receive standards 14 by which it is supported. The standards may be relatively long or short, according to whether it is desired to stand 40 the apparatus on the floor or on a bench. Each standard is provided at its lower end with a base 16 to stand on the floor or bench, as the case may be. The steam space of this chest is indicated at 18. One end of the steam-chest is formed with a boss to receive a steam supply pipe 20 and the other end is formed with a boss to receive an exhaust or return pipe 22. These pipes are provided with valves 24 and 26 respectively 45 to control the admission and escape of the steam and to regulate the fluid pressure in the steam-chamber 18. The upper wall of the steam-chamber is indicated at 28, and above this wall and separated therefrom is a horizontal wall 30 which forms the bottom of a series of individual work stations or treating chambers 32. The space 34 between the walls 28 and 30 constitutes a vaporizing chamber into which water is de- 50 livered and converted in vapor as herein-

after described, the wall 30 having holes 36 through which the vapor may rise from the chamber 34 to enter the treating chambers 32. A series of upright walls 38 form the sides of the treating chambers and are 70 connected by a continuous rear wall 40 and by an inclined top wall 42. Each chamber 32 is therefore in the form of a cowl and is of a size suitable to receive the forepart of a shoe. As shown by Fig. 2, the steam-chest projects to the rear of the treating chambers, and the portion so projecting is provided with a standpipe 44 through which the water is conducted downwardly from a supply valve 46. A cup or funnel 48 is preferably attached to the upper end of the pipe 44 to receive the water from the valve. The cup and valve are preferably located above the level of the top of the unit 10 to enable the user to observe the rate 80 at which the water is discharging.

A condenser 50 is arranged under the steam-chest and is in communication with the latter by means of a short section of pipe 52. This condenser is supported in part by the pipe 52 and in part by brackets 54, and except for these connections, which have no appreciable heat-conducting capacity, the condenser is thermally insulated from the steam-chest and is almost wholly surrounded by the atmosphere and therefore maintained at relatively low temperature. Any water of condensation that is formed in the steam-chest will be drained by gravitation into the condenser 50 by the pipe 52, and to promote such drainage the bottom wall of the steam-chest is formed with a trough 56 leading to the pipe 52. The condenser 50 is preferably made of a cylindric section of relatively large pipe and two pressure-tight headers or screw caps 58. The inlet pipe 52 is screwed into the top of the condenser, while a discharge pipe 60 drains water by gravitation from the bottom of the condenser and conducts it to the valve 46 hereinbefore mentioned.

The low part of the pipe 60 is U-shaped to provide a seal-forming trap by which steam is prevented from escaping with the water of condensation. By reason of its location the trap is maintained at a temperature but little if any hotter than the atmosphere. Furthermore, the water by which the seal is formed and replenished is supplied by the condenser which, being interposed between the steam-chest and the water-seal, maintains the seal with water of relatively low temperature irrespective of the temperature of the steam-chest. With this construction the internal fluid pressure in the chamber 18 obtains in the pipe 52, in the condenser 50 and in the pipe 60, and is the moving force by which the water of condensation is elevated to and discharged from the valve 46.

The water delivered into the cup or funnel

48 flows by gravity through the pipe 44 and enters a small recess or receiving chamber 35 at the rear of and adjoining the vaporizing chamber 34. As shown by Fig. 1, the 5 chamber 35 is midway between the ends of the series of treating chambers, that is, in register with the partition that divides the second and third treating chambers from each other. The water delivered by the pipe 10 44 flows upon the wall 28 of the steam-chest which wall is commonly, though not necessarily, maintained at a temperature considerably hotter than the boiling temperature but which is subject to regulation in the matter 15 of temperature by adjustment of the valves 24 and 26. The upper surface of the wall 28 has sloping areas 62 in register with the second and third chambers 32, and oppositely pitched sloping areas 63 in register 20 with the first and fourth chambers. These sloping areas form valleys in register with the partitions between the first and second chambers and the third and fourth chambers. The water delivered to the receiving 25 chamber 35 is therefore divided into two streams which flow in opposite directions on the sloping areas 62 and are arrested by the oppositely sloping areas 63 and then almost immediately converted into vapor. The vapor-generating localities are thus localized 30 in the aforesaid valleys so that the several chambers 32 all receive substantially equal quantities of vapor. This feature guards against the aforesaid harmful practice of 35 staining or burning some of the shoes by furnishing too much vapor to them under conditions of unequal distribution of vapor.

When the apparatus is in operation, the 40 temperature of the entire cast iron unit 10 may be regulated by adjusting the valves 24, 26. These adjustments also regulate the internal fluid pressure in the steam-chest as well as that in the condenser and the water supply pipe 60. At first the steam admitted 45 to the chamber 18 will undergo considerable condensation by reason of the low initial temperature of the unit 10. The water of condensation thus formed will drain into the condenser 50 where it will be stored and 50 from which it will be discharged under control of the valve 46 as required. At the same time, steam enters the condenser 50 and is promptly condensed. The accumulation of water of condensation in the condenser is 55 rapid, and since the temperature of the condenser is always low it is impossible for steam to pass through the water and enter the pipe 60. Even when the unit 10 is heated to its highest temperature the comparatively cool water in the condenser prevents 60 the passage of steam and maintains a supply of water that keeps the condenser filled and the water-seal intact. The water of condensation is always under pressure equal to 65 that in the steam-chest, which pressure need

not be more than two or three pounds per square inch to effect its discharge when the valve 46 is open.

The walls forming the treating chambers 32 are integral parts of the iron casting 10 70 in which the steam chamber 18 is formed. Consequently, these walls of the casting become heated to a high temperature whether treating vapor is generated or not, and radiate heat to the shoes. If it is desired to supplement the radiant heat by hot moist vapor, it is only necessary to open the valve 46, whereupon the water discharged by the valve will be delivered to the upper surface of 75 the wall 28 by which it is divided in two streams and distributed, is hereinbefore explained, and almost immediately converted 80 into vapor. The vapor is baffled more or less and distributed laterally by the horizontal wall 30 but rises through the holes 36 in said 85 wall and then passes directly to the articles of work.

The drawings also illustrate a preferred type of work-supporting means by which a series of pulled-over shoes may be supported 90 right side up or bottom side up as desired. The work-supporting means is not claimed in this application since it has heretofore been disclosed and claimed in my copending application Serial No. 616,602, filed February 2, 1923. Nevertheless, the following is 95 a brief description of said means.

A board of wood or any other suitable heat-insulating material 70 is fastened to the front upright surface of the steam-chest 100 by clamping bolts 72 and is provided with vertical slots 74 to afford a range of vertical adjustment. As shown in Fig. 1, the upper edge of this board is formed with a series of curved notches or recesses 76 that register 105 respectively with the treating chambers 32 while the lower edge 78 is straight and horizontal. These two different formations are provided for different uses since the board is intended to be inverted when the shoes are to stand right side up as hereinafter explained. Another board, indicated at 80, is connected to the board 70 by two metallic supporting bars 82. These bars are pivotally connected to the ends respectively of 110 the board 70 by bolts 84 the threads of which co-operate with internal threads formed in the board 70 so that when the bolts are set up tightly they will clamp the bars to hold them rigidly in whatever position they are placed. The board 80 is connected to the bars 82 by clamping bolts having knobs 86, these bolts extending through slots 88 in the bars and being adapted to clamp the board 80 to the bars at any desired position within 115 the range of the slots and also permitting the board 80 to be turned about the axis of said bolts. One edge of the board 80 is formed with a series of notches 90 which register respectively with the treating chambers 120 125 130

bers 32. The notches 90 are preferably V-shaped to conform approximately to the so-called cone portion of the last. Thus, when the boards 70 and 80 are in the relation shown by Fig. 3, they will maintain the shoes in inverted position with the foreparts occupying the treating chambers 32.

If it is desired to support the shoes right side up for treatment, as shown in Fig. 2, 10 the board 70 will be inverted and its straight, horizontal edge 78 will be at a level far enough above the bottom wall 30 of the treating chambers to maintain the depending marginal portions of the uppers from 15 touching said wall. At the same time the board 80 will be turned about the axis of the clamping bolts 86 so that one of its straight surfaces will be uppermost and nearly if not quite horizontal. One of its flat major 20 surfaces or its straight edge may be used for this purpose, both of which uses are shown in Fig. 2. The desired elevation of the board 80 is afforded by angular adjusting movement of the bars 82 about the axis of the 25 bolts 84. In this case, the upper surface of the board 80 and the straight, horizontal upper surface of the board 70 constitute a flat, if not always a level, platform on which the bottoms of the pulled-over shoes may 30 stand.

If it is desired to confine the vapor in the treating chambers by restricting the openings through which the foreparts are inserted, the treating chambers may be provided 35 with adjustable plates 92. These plates are connected individually to the rear walls of the treating chambers by hinges 94 but their forward portions project beyond the treating chambers and are all connected by a rod 40 96 to afford convenient means by which they may be adjusted collectively. An adjustable supporting link 98 is connected to the rod 96, as here shown, by being formed with an eye through which the rod extends. This 45 link is clamped to a bracket 97 by a clamping bolt 95, the link having a slot 99 to afford the necessary range of adjustment. The bracket 97 is affixed to the top of the 50 structure forming the chambers 32. This feature comprising the adjustable plates 92 is not herein claimed since it is disclosed and claimed in my aforesaid copending application Serial No. 616,602.

Having thus described my invention, what 55 I claim as new and desire to secure by Letters Patent of the United States is:

1. In an apparatus for treating shoe materials comprising a steam-chest, the combination therewith of a condenser thermally 60 insulated from said steam-chest but in communication therewith to receive steam, means to supply water of condensation from said condenser to an upper surface of said steam-chest to be thereby converted into hot moist vapor, and means to support an arti-

cle of work in position to be treated by the vapor so produced.

2. An apparatus for treating shoe materials comprising a pressure-sustaining steam-chest, means to drain water of condensation 70 by gravitation from the bottom of said chest and deliver it to an upper surface thereof to be converted into vapor, said means being arranged to form a water-seal below the level of said bottom, and means to support 75 an article of work in the field of such vapor.

3. An apparatus for treating shoe materials comprising a steam-heated structure having a pressure-sustaining steam-chest for radiating heat to the work, and means to drain water of condensation from the bottom of said steam-chest and deliver it to an external surface thereof to be thereby converted into vapor, said means being arranged 80 to form a water-seal remote from thermal 85 influence of said steam-chest.

4. An apparatus for treating shoe materials comprising a steam-heated structure including a pressure-sustaining steam-chest for radiating heat to the work, means to 90 drain water of condensation downwardly from the bottom of said steam-chest and deliver it to an external surface of said structure to be converted into hot moist vapor, said means including a pressure-sustaining 95 condenser below the level of the bottom of said steam-chest, and means to support an article of work in the field of vapor generated by said surface.

5. In an apparatus for treating shoe materials comprising a steam-chest and means to support the work in the field of radiant heat adjacent thereto, the combination therewith of a condenser thermally insulated from said steam-chest but in communication 100 therewith to receive steam, and means to supply water of condensation from said condenser to an external surface of said steam-chest to be thereby converted into hot moist 105 vapor to treat the work.

6. In an apparatus for treating shoe materials comprising a steam-chest and means to support the work above and adjacent thereto, the combination therewith of a condenser arranged under and thermally insulated from said steam-chest but in communication therewith to receive steam and drain water of condensation therefrom, and means to supply water of condensation from 110 said condenser to an upper surface of said steam-chest to be thereby converted into hot moist vapor to treat the work.

7. In an apparatus for treating shoe materials comprising a steam-chest, the combination therewith of a pressure-sustaining 115 reservoir separate from and at a lower level than said steam-chest but in communication therewith to receive steam and to drain the water of condensation from the steam-chest, means to supply water of condensation from 120 125 said reservoir to an upper surface of said steam-chest to be thereby converted into hot moist vapor to treat the work.

130

said reservoir to an external surface of said steam-chest to be thereby converted into hot moist vapor to treat the work, and means to support the work in position to be treated by such vapor.

8. In an apparatus for treating shoe materials comprising a steam-chest and means to support the work adjacent thereto, the combination therewith of an elongated pressure-sustaining reservoir separate from but in communication with said steam-chest to drain water of condensation therefrom, the major dimension of said reservoir being horizontal, and means to supply water of condensation from said reservoir to an external surface of said steam-chest to be thereby converted into hot moist vapor to treat the work.

9. In an apparatus for treating shoe materials comprising a pressure-sustaining steam-chest and means to support the work in the field of radiant heat adjacent thereto, the combination therewith of a conduit arranged to drain water of condensation downwardly from the bottom of said steam-chest and deliver the same to an upper surface of said steam-chest to be thereby converted into hot moist vapor to treat the work.

10. In an apparatus for treating shoe materials comprising a steam-chest and means to support the work adjacent thereto, the combination therewith of a conduit arranged to drain water of condensation downwardly from the bottom of said steam-chest and deliver the same to an external surface of said steam-chest to be thereby converted into hot moist vapor to treat the work, said conduit including an intermediate storage chamber thermally insulated from and below the level of said steam-chest to store water of condensation for delivery as aforesaid.

11. An apparatus for treating shoe materials comprising a steam-heated unit having a pressure-sustaining steam-chest, a vaporizing chamber above and contiguous to said steam-chest, and a work-treating chamber above and contiguous to said vaporizing chamber, said chambers having one or more communicating passageways for vapor and said steam-chest and said work-treating chamber being thermally related so that the steam-chest will supply and the walls of the treating chamber will radiate heat to the work independently of the treating vapor, and means to supply water of condensation to said vaporizing chamber from the steam and water of condensation in said chest.

12. In an apparatus for treating shoe materials comprising a steam-chest and means to support the work adjacent thereto, the combination therewith of a pressure-sustaining reservoir for condensing steam into water, a conduit arranged to drain water of condensation and conduct steam from said steam-chest to said reservoir, and means to

supply water from said reservoir to an upper surface of said steam-chest to be thereby converted into hot moist vapor to treat the work.

13. An apparatus for treating shoe materials comprising a steam-heated unit having an elongated horizontal steam-chest, a vaporizing chamber above and contiguous to said steam-chest, and a series of work-treating chambers above and in communication with said vaporizing chamber, a pressure-sustaining water-reservoir supported under said steam-chest, a conduit arranged to drain water of condensation and conduct steam from said steam-chest to said reservoir, and means to supply water from said reservoir to said vaporizing chamber to furnish vapor for treating the work.

14. An apparatus for treating shoe materials comprising means forming a series of treating stations side by side, a heat-radiating element underlying each of said stations, and means to deliver water to an upper surface of said heat-radiating element, said upper surface having areas that slope downwardly in different directions from the locality at which the water is delivered thereto to distribute the water under a plurality of said stations.

15. An apparatus for treating shoe materials comprising means forming a series of treating stations side by side, a heat-radiating element underlying each of said stations, and means arranged to deliver water to an upper surface of said heat-radiating element at a point between two of said stations, said surface having areas that slope downwardly and laterally in opposite directions from said point to divide the water into separate streams and distribute the water under a plurality of said stations.

16. An apparatus for treating shoe materials comprising means forming a series of treating stations side by side, a heat-radiating element underlying each of said stations, and means arranged to deliver water to an upper surface of said heat-radiating element at a point out of register with each of said stations, said surface having angularly related areas that slope downwardly from said point and extend under a plurality of said stations to distribute the water while it is being heated.

17. An apparatus for treating shoe materials comprising a horizontally elongated heat-radiating element, means arranged to support a series of articles of work to be treated over and adjacent to said element, means arranged to discharge water on an upper surface of said heat-radiating element which surface extends under the stations to be occupied by the articles of work and is formed to divide the water into separate streams and distribute the latter to separate localities, and baffle means arranged to

equalize the distribution of vapor rising from said surface to the articles of work.

18. An apparatus for treating shoe materials comprising a series of individual treating chambers separated from each other by partitions, a heat-radiating element having an upper surface extending under each of said chambers, and means to deliver water to said surface to be converted thereby into hot moist vapor to treat the articles of work in said chambers, said surface having a series of inclined areas in register with said chambers respectively and forming valleys in register with certain of said partitions to divide the water into separate bodies and localize such bodies.

19. An apparatus for treating shoe materials comprising a steam-heated structure having a steam-chest, means forming one or more treating chambers above said steam-chest, a water-conduit the receiving end of which is above the level of the top of one of said chambers and in a field of observation, and the discharge end of which is arranged to discharge the water on an upper surface of said steam-heated structure extending under said one or more treating chambers, and a pressure-sustaining conduit in communication with said steam-chest and leading downwardly from the bottom of said chest and thence to a point above and in register with said receiving end of the first said conduit to supply water of condensation to the latter, said pressure-sustaining conduit having a regulating valve and the space between the adjacent ends of said conduits affording observation of the water passing from one conduit to the other.

20. An apparatus for treating shoe materials comprising a steam-heated structure having a pressure-sustaining steam-chest, a pressure-sustaining reservoir thermally insulated from said steam-chest but arranged to drain water of condensation therefrom, a conduit arranged to drain water from the bottom of said reservoir and deliver such water to an external surface of said steam-heated structure to be converted into hot moist vapor to treat the work, and means to support the work in position to be treated by such vapor.

21. An apparatus for treating shoe mate-

rials comprising a pressure-sustaining steam-chest, means for supporting the work in the field of heat radiated therefrom, and a conduit arranged to drain water of condensation downwardly from the bottom of said steam-chest and deliver such water to an external surface of the latter to furnish vapor for the work, said conduit including a condenser and a trap to form a water-seal both of which are thermally insulated from said steam-chest.

22. An apparatus for treating shoe materials comprising a pressure-sustaining steam-chest, means for supporting the work in the field of heat radiated therefrom, and a conduit arranged to drain water of condensation downwardly from the bottom of said steam-chest and deliver such water to an external surface of the latter to furnish vapor for the work, said conduit including a seal-forming trap and a condenser below the level of and thermally insulated from said steam-chest, and said condenser being interposed between the steam-chest and said trap.

23. An apparatus for treating shoe materials comprising a steam-heated structure including a pressure-sustaining steam-chest, means to drain water of condensation from the bottom of said steam-chest and deliver it to an upper surface of said structure to be converted into hot moist vapor, said means including a pressure-sustaining condenser to condense any steam received from said steam-chest, and means to support an article of work in the field of vapor generated by said surface.

24. In an apparatus for treating shoe materials comprising a steam-chest and means to support the work adjacent thereto, the combination therewith of a conduit arranged to drain water of condensation from said steam-chest and deliver the same to an external surface of said steam-chest to be thereby converted into hot moist vapor to treat the work, said conduit including an intermediate storage chamber thermally insulated from said steam-chest to store water of condensation for delivery as aforesaid.

In testimony whereof I have signed my name to this specification.

FREDERICK M. FURBER.
